TUFTING ATTACHMENT FOR SEWING MACHINES

Ernest Wilbur Jackson, Chatsworth, Ga., assignor
or of one-third to Ben J. Chromy, Washington,
D. C.

Application October 20, 1938, Serial No. 236,100

9 Claims. (Cl. 112—79)

This invention relates to tufting devices adopted to be attached to sewing machines of the reciprocating needle type to enable the aforesaid sewing machines to produce chenille decorations in clothes of various descriptions.

An object of this invention is to provide a simple chenille attachment for the sewing machine to permit the machine and attachment to be operated at high speeds heretofore not attainable except perhaps only for very short intervals.

Another object of this invention is to provide a chenille sewing machine attachment constructed in such a way that it may be balanced and adjusted to facilitate high speed operation for extended periods of time.

A further object of this invention is to provide a chenille machine attachment constructed in such a way that various parts of the attachment are subjected to continuous rotary motion whereby the sewing machine and the attachment may be operated at relatively high speeds without introducing excessive vibrations into the mechanism.

Still another object of this invention is to provide a chenille sewing machine attachment with a rotating loop cutter and a rotating hook which rotates in opposite direction from that of the cutter and receives the thread loop in such a way that cutting of the formed loops is easily and readily accomplished while the rotary hook is in continuous forward rotation.

Other and further objects of this invention will be apparent to those skilled in the art to which it relates from the following specification and 35 claims:

In accordance with this invention I provide a tufting device attached to sewing machines of the reciprocating needle type. The device of my invention is constructed in a simple manner in such a way that it may be used for long periods of time at relatively high speeds and thus the output of chenille decorations made by each sewing machine equipped with this invention, increased.

The attachment of my invention consists essentially of two moving parts, that is, a rotary cutter and a rotary hook both of which are geared through suitable beveled gears to the sewing machine which may be of the Singer type in such a way that one revolution is imparted to each of these elements each time a loop is formed by the needle of the sewing machine. In a modified form of my invention I have shown that the cutter need not be rotated and this will be explained in detail in the following specification.

The rotary hook is preferably formed in the shape of a single turn helix or spiral so that during the operation thereof a previously formed loop is cut or severed at about or just after the time that another loop is being or is received on the rotary hook from the sewing machine needle. A surface of the rotary hook is made of material that may be ground to receive a sharp edge and cooperate with the cutting edge of the rotary cutter for the purpose of shearing the loop thread. The shearing surfaces are formed in such a way that the thread is gradually and easily cut to prevent unnecessary strain on the cutting mechanism particularly if bulky thread is being used.

Various other features of this invention will be more fully described in the following specification and the drawings, in which, briefly, Fig. 1 is a side view partly in cross-section of the sewing machine showing my attachment in place; Fig. 2 is a bottom view illustrating my attachment on a sewing machine; Fig. 3 is an end view in partial section showing my invention; Fig. 4 is a sectional view taken along the line 4—4 of Fig. 3 showing the rotatable hook and knife; Fig. 5 is a sectional view taken along the line 5—5 of Fig. 4; Fig. 6 is a sectional view similar to Fig. 4 showing the hook and knife advanced through a part of their cycle of operation; Fig. 7 is a view taken along the line 7—7 of Fig. 6; Fig. 8 is another sectional view similar to Fig. 4 showing the hook and knife about to complete a cycle of operation; Fig. 9 is a perspective view of the principal part of my tufting attachment; Fig. 9a is an enlarged cross-sectional view along the line 9a—9a of Fig. 9 of the rotatable hook to show the minute ridges thereon; Fig. 10 illustrates the appearance of the cut and uncut loops inserted into the cloth; and Fig. 11 is another view illustrating the ends of the cut loops projecting from the cloth surface.

Referring to Figs. 1, 2 and 3 of the drawings in detail reference numeral 1 designates a sewing machine of the Singer type in which a needle 2, carried by the plunger 3, is reciprocated up and down and carries thread loops down through cloth that is moved over the base 4 underneath the shoe 5 through the operation of an oscillating cloth advancing device 6. While the cloth is being advanced over the table 4 and thread loops are being produced, the ring-like hook 7 and cutter 8 associated therewith, are rotated by a differential gear arrangement including relatively small beveled gears 9, 10, and 10a. The gear 10 is mounted on the shaft 11 and is connected by worm gears 12 to the shaft 13. The shaft 13 is driven by worm gears 14 from the main shaft 15.

of the sewing machine which also is mechanically connected to the reciprocating needle actuating-plunger 3 to move this plunger and needle up and down. The rotatable hook 7 and knife 8 are thus operated in step or synchronism with the reciprocating movement of the needle 2. The rotatable hook 7, knife 8, and the beveled gear wheels 9 and 10a are supported by the shaft 16 which is journaled in the members 17 and 18. The bearing members 17 and 18 are attached to projections 21 and 22, carried by the sewing machine table 4, by the bolts 19 and 20, respectively. The position of the hook 7 may be altered slightly with respect to the needle 2 and the table 4 of the sewing machine by loosening the bolts 19 and 20 and moving the shaft 16 and bearings 17 and 18 a limited amount determined by the size of the holes formed in the bearing members 17 and 18 for the bolts 19 and 20, respectively. An adjustment such as this is desirable inasmuch as the point 7a of the hook 7 should be adjusted to come as close as possible to the needle 2 in order to be able to enter the thread loop formed by the needle 2 just as this needle is being drawn upward from the lowermost position in its cycle of operation. The manner in which the needle forms the thread loop may be observed from Fig. 5 of the drawings, where the needle 2 is shown shortly after its upward movement was initiated. The point 7a of the hook 7 is in this case advancing toward the needle to enter the thread loop. When the point 7a of the hook 7 enters the thread loop between the thread 23 and the needle 2 the loop is caught by the hook so that when the needle 2 is drawn still further upward through the cloth 24 the thread loop is held beneath the lower surface of the cloth by the aforesaid hook. At the same time as the needle 2 is moved upwards the hook 7 is rotated in the counterclockwise direction indicated by the arrow in Fig. 6, by means of the beveled gear 9 which is attached to or formed integral with the bearing portion 7b of the hook 7 as illustrated in Fig. 7. Before the needle 2 is returned downward to form the next thread loop the cloth 24 is advanced in the direction indicated by the arrow in Fig. 7 by means of a conventional cloth advancing mechanism 6 shown in Figs. 1, 2 and 3. During its next downward movement the needle 2 pierces another hole through the cloth 24, carrying the thread 23 with it as before. By the time the needle is moved downward into its lowermost position the second time the previously formed loop, caught by the hook 7, is wound over the helical portion of the hook and is about to be cut by the rotatable knife 8 and the cutting surface 7c of the rotatable hook, as shown in Fig. 8.

The hook 7 is ready to receive the second loop being formed by the needle 2 in the view illustrated in Fig. 8. The second loop being formed resembles the thread loop illustrated in Fig. 5. At this time the first loop is about to be cut by the cutting edge of the knife 8 cooperating with the cutting edge of the knife 7c. In other words the first loop has been wound completely around the hook 7 and is severed approximately at the time the second or next loop is being received by the hook point 7a. The cutting operation performed by the rotatable knife and the cutting edge 7c is accomplished by revolving the knife 8 in the opposite direction to that in which the hook is rotated. This is accomplished through the differential gear mechanism employing the gears 9, 10 and 10a. The gear 10a is fixedly attached to the shaft 16 and the knife 8 is likewise

attached to this shaft so that the gear 10a rotates the knife 8. The gear 9 is attached to the hook 7 and rotates this hook. In certain cases it may be desirable not to rotate the knife 8 and in that case the shaft 16 carrying this knife may be held fixed leaving the knife in one position, for example, the position illustrated in Fig. 8 or some similar position where the formed loops may be readily severed. The gear 10a would be dispensed with in this case. Where desired the time of the cutting operation may be slightly altered from the time at which this operation will take place according to the showing in Fig. 8. This may be accomplished by loosening the set screws holding the knife 8 in position on the shaft 16 and either advancing the knife toward the cutting edge 7c or retarding it therefrom. Furthermore if it is desired to advance or retard the time when the hook receives the thread loop from the needle, this may be accomplished by loosening one of the joints, for example joint 11a in the shaft 11 and then slowly rotating the fly wheel of the sewing machine until the proper relationship between the needle 2 and hook 7 is obtained. For example, if it is desired to obtain the relationship shown in Fig. 8 the hook 7 may be rotated until it is in the position shown irrespective of the position of the needle and then the coupling in the shaft 11 may be loosened so that the needle 2 may be moved while the hook remains stationary until the desired relationship is obtained. After the desired relationship is obtained between the hook and needle the coupling in the shaft is again set so that the hook may be rotated in synchronism with the needle. It is of course obvious that these adjustments may be made without employing a coupling in the shaft 11 if one of the worm wheels 12 is provided with an adjustment set screw so that these worm wheels may be rotated without rotating the shaft 11 by releasing a suitable set screw. Furthermore where desired the worm wheels 12 and 14 may be replaced by a suitable chain drive if desired.

In Figs. 10 and 11 I have illustrated samples of tufting that may be produced with the machine of my invention. The view shown in Fig. 10 illustrates a plurality of loops that have been severed after they were inserted into the cloth 24 and one loop which is not yet severed. The cord 23 was severed at a series of places 23b, 23c, 23d and 23e producing loose ends corresponding to the reference numerals. In each case the previously formed loop was severed when the next loop was being formed. For instance the ends 23f were formed from the thread loop at the time that the loop 23a was being formed and this loop 23a would be or about to be cut when the next loop was being formed. After the threads are inserted as shown in Fig. 11 the thread ends 23g are brushed, combed or otherwise manipulated to bring about a tuft appearance. In order to produce this appearance the fibers forming each of the cords or threads must be separated from each other to give a bushy appearance.

The length of the tufting also may be regulated in accordance with this invention by making the hook and knife arrangement and the bearings therefore movable toward or away from the table 4 of the sewing machine. Some adjustment may be obtained by adjusting the bolts 19 and 20 as was described. However, the attachment of my invention may be movable as a unit through the use of suitable mounting bolts for mounting the unit upon the leg 4a together with 75

a bearing for the shaft 11. In that case a slot would be provided in the leg 4a for the shaft instead of a bearing and a small universal joint would be employed in the shaft in place of the coupling employed. Where desired a relatively thin section may be cut from the leg 4a adjacent to the tufting attachment and this section may be bolted back to the leg 4a to permit the attachment to be moved with respect to the table 4 to 0 a slight extent.

The hook 1 is provided with minute ridges as shown in the enlarged cross-sectional view Fig. 9a, extending longitudinally over the length thereof for the purpose of gripping the thread 5 to prevent same from sliding around the hook after the needle is withdrawn from the cloth as shown in Fig. 7. These ridges are preferably very small and may be formed in the hook by rubbing the hook with a piece of fine emery 10 cloth longitudinally. These ridges provide a certain amount of friction to reduce the transverse movement of the thread across the hook. They do not however interfere with the passage of the hook through the loop. The point 1a of the hook 15 is preferably made relatively blunt as illustrated in the drawings. In this way the size of the loop is made large enough for any cross section of the hook and the friction on the hook is thereby reduced since the loop does not have to be increased in size as would be the case if the cross 20 section of the hook gradually increased were the point made fine and long.

It will be observed that I have described a 35 practical embodiment of this invention in detail in the foregoing specification. However I do not desire to limit this invention to the exact details described except in so far as these details may be defined by the claims.

What I claim is:

40 1. In a chenille sewing machine attachment adapted to be attached to a sewing machine having a reciprocating needle, the combination of: a rotatable substantially helical hook having a pointed free end adapted to pass along side of the needle of the sewing machine and receive a thread loop from said needle, a bearing for said rotatable hook, a gear for driving said rotatable hook, a shaft extending through said bearing, a 45 rotatable knife attached to said shaft and rotatable adjacent to said rotatable hook, a surface of said rotatable hook being formed to cooperate with said rotatable knife to form a shear for severing the thread loop passed over said hook, a second bevel gear attached to said shaft and means for rotating said first mentioned bevel gear and said second bevel gear in time relation with the reciprocating movement of the needle of the sewing machine.

60 2. In a chenille or tufting sewing machine attachment adapted to be attached to a sewing machine having a reciprocating needle, the combination of: a substantially spiral shaped rotatable hook comprising a substantially complete annular turn having a pointed free end and adapted to pass along side of the needle of the sewing machine and receive a thread loop from said needle, a bearing for said rotatable hook, a shaft extending through said bearing, a rotatable knife attached to said shaft and rotatable adjacent to said rotatable hook, a surface of said rotatable hook being formed to cooperate with said rotatable knife to form a shear for severing the thread loop passed over said hook, gear means 65 attached to said shaft for rotating said hook and

said knife in time relation with the reciprocating movement of the needle of the sewing machine.

3. In chenille sewing machine attachment adapted to be attached to a sewing machine having a reciprocating needle, the combination of: 5 a substantially spiral shaped rotatable hook having a pointed free end adapted to pass along side of the needle of the sewing machine and receive a thread loop from said needle, a sleeve for supporting said rotatable hook, a shaft extending through said sleeve, a knife attached to said shaft and positioned adjacent to said rotatable hook, a surface of said rotatable hook being formed to cooperate with said knife to form a shear for severing the thread loop passed over said hook, 10 gear means attached to said sleeve for rotating said hook in definite time relation with the reciprocating movement of the needle of the sewing machine.

4. In a chenille sewing machine attachment adapted to be attached to a sewing machine having a reciprocating needle, the combination of: a rotatable substantially circular hook having a pointed free end adapted to pass along side of the needle of the sewing machine and receive a thread loop from said needle, a sleeve attached to said rotatable hook, a gear attached to said sleeve for rotating said hook, a shaft extending through said sleeve, a rotatable knife attached to said shaft, a surface of said rotatable hook being formed to 20 cooperate with said rotatable knife to form a shear for severing the thread loop passed over said hook, and means for rotating said gear and said shaft in time relation with the reciprocating movement of the needle of the sewing machine. 25

5. A chenille sewing machine attachment, comprising: a rotatable hook formed to include at least one turn of a helix-like element and having a pointed free end for receiving thread loops as 30 they are formed by the sewing machine needle, the inside surface of said hook being provided with minute longitudinal grooves to guide the thread loop; a hollow bearing member, the other end of said hook being attached to said hollow bearing member, a shaft extending through said 35 hollow bearing member, means for rotating said rotatable hook in time relation with the operation of the sewing machine needle, a cutting member supported adjacent to said rotatable hook, said cutting member being arranged to cut 40 through a formed thread loop just as another thread loop is being formed and received by the pointed free end of said hook.

6. A chenille sewing machine attachment, comprising: a continuously rotatable hook formed 55 substantially in the shape of a helix including at least one turn having a pointed free end for receiving thread loops as they are formed by the sewing machine needle, a bearing member, the other end of said hook being attached to said bearing member, means for rotating said rotatable hook in time relation with the operation of the sewing machine needle, a cutting member, means for rotating said cutting member against the rotation of said hook, said cutting member 60 being supported adjacent to said rotatable hook for cutting the formed thread loops at predetermined intervals during the rotation of said rotatable hook, said rotatable hook being formed in the shape of a helix having at least one turn 65 so that a thread loop may be threaded on said hook substantially at the supported end of said hook in position for cutting by said cutting member as said pointed free end is positioned to receive another thread loop. 70

7. A chenille sewing machine attachment, comprising: a rotatable hook formed substantially in the shape of a helix having at least one turn with a pointed free end for receiving thread loops as they are formed by the sewing machine needle, means for continuously rotating said rotatable hook in time relation with the operation of the sewing machine needle, a cutting member, means for continuously rotating said cutting member against the rotation of said hook, said cutting member extending radially with respect to said rotatable hook and adjacent thereto for cutting the formed thread loops at predetermined intervals during the rotation of said rotatable hook, said rotatable hook being formed in the shape of a helix having at least one turn so that a thread loop may be threaded on said hook while another thread loop is being formed and positioned to be received by the pointed end of said hook.

8. A chenille sewing machine attachment adapted to be attached to a sewing machine having a reciprocating needle, the combination of: a rotatable hook formed substantially in the shape of a helix having at least one turn with a pointed free end for passing along side of the needle to receive thread loops substantially as they are completed, means for continuously rotating said rotatable hook in time relation with the operation of the sewing machine needle, a rotatable cutting member adapted to rotate adjacent to a surface of said hook to shear formed thread loops against said hook surface at selected intervals, the plane of rotation of said cutting member being substantially displaced from the plane of rotation of said pointed free end of said hook so that thread loops may be received by said pointed end of said

hook and threaded on said hook toward said cutting hook surface and into the plane of rotation of said cutting member simultaneously as said needle is reciprocated to form another thread loop to be received by said pointed end of said hook.

9. A chenille sewing machine attachment, comprising: a continuously rotatable hook formed substantially in the shape of a helix including at least one turn having a pointed free end for receiving thread loops as they are formed by the sewing machine needle, a bearing member, the other end of said hook being attached to said bearing member, means for rotating said rotatable hook in time relation with the operation of the sewing machine needle, a cutting member, means for rotating said cutting member against the rotation of said hook, said cutting member being supported adjacent to said rotatable hook for cutting the formed thread loops at predetermined intervals during the rotation of said rotatable hook, said rotatable hook being formed in the shape of a helix having at least one turn so that a thread loop may be threaded on said hook substantially at the supported end of said hook in position for cutting by said cutting member as said pointed free end is positioned to receive another thread loop, a frame, a bolt supported by said frame, said bolt engaging said bearing member whereby said rotatable hook may be adjusted to and away from the cloth so that tufting of different nap length may be obtained by loosening said bolt and moving said bearing means closer to or further away from a chosen position of said needle.

ERNEST WILBUR JACKSON.
